assignors to Siemens Brothers & Company
Limited, London, England

Application May 17, 1935, Serial No. 22,032
In Great Britain June 21, 1934

17 Claims. (Cl. 179—16)

The present invention relates to electric remote control systems and more particularly to such systems in which control is exercised by means of electric current impulses as, for example, automatic telephone systems. The current impulses in such systems are ordinarily intermissions of direct current.

A desirable feature in such systems is an ability to transmit signals over the control circuit during the transmission of ordinary trains of current impulses and receive and utilize the same. It may also be desired to transmit signals prior and/or subsequent to an ordinary train.

The present invention has in view arrangements to this end and more specifically arrangements in which the signals are themselves in impulse form. It will be appreciated that such arrangements would allow of the transmission of more than one train of impulses simultaneously or by the employment of suitable receiving apparatus, allow of special circuit changes being made at the receiving end prior to or subsequent to the transmission of an ordinary train of impulses.

The ordinary rate of impulsion in electric remote control systems of the kind mentioned is comparatively low, of the order of 10 impulses per second. The signals utilized in the present invention consist of circuit closures or interruptions of a much shorter duration such as may be termed fleeting signals. Their duration is such as would be occasioned by the make through period of a make-before-break contact of a relay adapted to receive ordinary impulses or by the change over of a contact of such a relay from its back to its front position or vice versa. The signals accordingly may have a duration of the order of 2 milliseconds.

For the generation of such signals various arrangements may be employed; for instance, if a signal has to be transmitted prior to the transmission of an ordinary train the off-normal contacts of a number dial may bring about closure of a charging circuit for a condenser in series with a relay, the relay operating by the charging current and consequently opening and closing the impulse circuit or again, in machine impulsing rotating cams may give rise to a condition corresponding to the make through condition of a relay.

At the receiving end must be provided a relay capable of responding to such fleeting signals such as a relay (hereinafter generically referred to as a high speed relay) of the type described

in Patent 1,992,610 of Ernest J. Gachet, issued Feb. 26, 1935.

Since however ordinary impulses are to be received also, it is preferable that the slower relay which responds to the ordinary impulses and controls switches accordingly should itself receive impulses repeated by the high speed relay (i. e. that receiving the fleeting signals).

Fleeting signals transmitted during an ordinary train may be transmitted during the make periods of the ordinary train or during the break periods, the fleeting signals in the one case being a "break", in the other a "make". It is also possible to transmit fleeting signals during the make and the break periods of an ordinary train.

It may also be arranged that an ordinary train of impulses may be transmitted but not utilized at any particular time the impulses to be utilized being in the form of fleeting signals.

The invention and a manner of carrying it into effect will be clear from the following description taken in conjunction with the accompanying drawings which show embodiments of the invention by way of example.

In the drawings Fig. 1 shows in diagrammatic form the makes and breaks of impulses in a train of impulses and the fleeting circuit closures and interruptions contemplated in the present invention. Fig. 2 shows a method of generating a fleeting circuit interruption by a number dial at the commencement of an impulse train. Fig. 3 shows arrangements for receiving signals comprising fleeting circuit interruptions during the make portion of impulses of standard length. Fig. 4 shows a similar arrangement for receiving 3 impulse trains simultaneously. Fig. 5 shows how 3 simultaneous impulse trains may be transmitted and Fig. 6 a time chart of the closures of the cam contacts of Fig. 5 to facilitate the understanding of the transmitting arrangement.

Fig. 1 requires only a brief consideration. In this figure time is measured horizontally and current vertically. In (a) a series of impulses of current represented by the rectangles C are shown and in the intervening space or break between two current impulses are shown two fleeting circuit closures or makes, the duration of these compared with those of standard impulses shown at C being apparent. In a similar manner in (b) are shown fleeting circuit interruptions or "breaks" T during an otherwise standard impulse one break being shown prior to the transmission of the first impulse break and fleeting makes or circuit closures during the break periods of standard impulses. Standard

impulses may be taken to be of the order of 10 per second and with the ratio usually employed in automatic telephone systems, i. e. make: break::1:2 the duration of a standard pulse of current is of the order of 33 milliseconds. The duration of a fleeting signal on the other hand is of the order of 2 milliseconds.

A method of transmitting a fleeting "break" at the commencement of an impulse train will be apparent from Fig. 2. In this figure DK represents contacts of a dialling key such as may be used at a telephone operator's position, or switch hook contacts on a telephone instrument, is being the impulse springs of the dial and on the dial off-normal contacts. When the contacts DK are closed, a loop circuit is closed over contacts *ts* and *ts*. When the dial is turned off normal contact on closes and remains closed until the dial again reaches its normal position after transmitting a train of impulses. On the closure of contact on condenser Q is charged and relay TS is operated momentarily by the charging current. The time for which it is operated may be determined by the size of the condenser Q and the impedances in shunt and in series with it, and when the relay operates, contact *ts* opens interrupting the loop circuit. This interruption is only of very short duration and will not have any effect on an ordinary impulse receiving relay connected to the loop. Such an operation corresponds to the fleeting break T nearest the left hand side of Fig. 1 (b).

Consideration will now be given to the signal receiving arrangements shown in Fig. 3 suitable arrangements being assumed to be provided for the transmission of fleeting "breaks" during the transmission of a pulse of current in a train of standard impulses. In the upper part of the figure is shown in skeleton form the connection of an impulse receiving relay S over contacts *h* of a switching relay (not shown) to the two speaking wires incoming to an automatic telephone selecting switch. The relay S and the corresponding resistance in the other wire may be taken as being in a circuit available for use with any one of a number of similar selecting switches for its control. Relay S is a high speed relay capable of responding to breaks of a very short duration, e. g. of the order of 1 to 2 milliseconds. Of the relays concerned with impulse and signal repetition, A is a relay of the ordinary type used as impulse receiving relays in automatic telephone systems and capable of giving satisfactory response to impulses of the order of 10 per second. It will not respond to impulses or signals of the order of 2 or 3 milliseconds' duration such as will affect relay S. Relay B is a slow releasing release control relay, C is a dialling relay, P, PA and PB relays concerned with signal recording, relays P and PB being high speed relays similar to relay S, and DM is a stepping magnet adapted to be operated in response to standard impulses repeated by relay A.

The method of operation of the apparatus shown in response to standard impulses will be apparent from the following brief description. When the two wires incoming to the upper part of the figure are looped relay S operates and at its single contact *s1* closes parallel circuits for relays A, B and C (winding (I)). A rectifier R is included in the circuit for relay B to prevent possible deleterious effect on the release lags of these three relays. Relay A operates quickly and opens a point in the circuit of magnet DM at contact *a1* and prepares a circuit for relay PB.

Relay B on operating closes a point in the circuit for magnet DM at contact *b2* and a point in a circuit for relay P at contact *b1*. Standard impulses received by relay S are repeated at contact *s1*, relay A releasing during each break period. Contact *a1* on falling back closes the circuit for magnet DM which includes a holding winding (II) of relay C. The magnet operates and performs its stepping function either on the attraction or retraction of its armature. During the break portion of an impulse, contact *a1* being in its back position, relay P operates in a circuit from earth over contacts *s1*, *b1*, *pbl*, *pa2*, relay P, resistance, to battery. Contact *p1* closes but since contact *a1* is in its back position and relay P releases due to the change over of contact *s1* before relay A becomes fully operated no further circuit changes occur.

If, during the time relay A is steadily operated by the make period of an impulse, or during the preliminary energization of relay A prior to impulsing a fleeting break occurs in the circuit of relay S, that relay responds to the break but owing to its very short duration relay A does not have time to release consequently contact *a1* remains in its front position and the magnet DM is not energized. On the release of relay S by such an impulse relay P is operated as before and prepares at contact *p1*, a circuit for relay PB and winding (I) of relay PA. These relays are at this time short-circuited but immediately relay S re-operates relay PB operates in series with relay P which remains operated pending operation of the slower operating relay PA. Contact *pbl* disconnects back contact *s1* from the circuits shown within the dotted line rectangle and connects it over wire W to similar circuits the relays of which corresponding to PB and PA are connected over a contact corresponding to *p1* to the commoning point shown so as to be under the control of relay A. Shortly after the operation of relay PB relay PA operates in series with relay P and locks up over its winding (II) over contacts *pa3*, *b3* and any other contacts which may be included in this circuit. Contact *pa1* disconnects the operating circuits for relays PA and PB and contact *pa2* closes across the contacts *pbl* to maintain the signal circuit to wire W after the release of relay PB. It will now be clear that a further fleeting break signal during a period when relay A is steadily energized will pass a signal to a circuit connected to wire W which may be arranged so that a third fleeting break signal will pass to a third circuit and so on. The signals, by the operation of relays such as PA and PB may be arranged to bring about any desirable operation. It will be appreciated that by connecting a similar receiving circuit to the front contact of *s1* signals transmitted as fleeting makes during the break portion of impulses may be received. Details of such an arrangement are shown in Fig. 4 which illustrates an arrangement for the reception of three impulse trains simultaneously.

Reference will now be made to Fig. 4. In this figure relays A, B and C perform functions similar to those performed by the correspondingly designated relays in Fig. 3. Contact *s1* is a contact of a relay which corresponds to relay S in Fig. 3, relays P and PP correspond to relay P and relays QB, QQB and QM and QQM are responsive to fleeting breaks and makes respectively and are of the high speed type. Relay CA is provided to take care of the case in which there are fewer standard impulses than fleeting

makes and breaks. The standard impulses bring about the operation of magnet SDM and the fleet-
ing makes and breaks the operation of magnets MDM and BDM respectively. Rectifiers R1 and 5 R2 are provided for the reason previously given.

The operation of magnet SDM by standard impulses will now be described. On the closure of a loop circuit, contact s1, by the operation of a relay such as S in Fig. 3, completes circuits for 10 relays A, B and C (winding (I)). Contact a2 opens a point in the magnet circuit and contact a3 disconnects winding (II) of relay C. Contacts b1 and c1 close in the magnet circuit and also 15 prepare a holding circuit for relay C during pulsing. Standard impulses operating contact s1 bring about the intermittent de-energization of relay A which accordingly releases and re-operates as contact s1 falls back and comes up again. Since contacts a1 and s1 always occupy corresponding 20 positions under the impulsive conditions now being considered, relays QB, QQB, QM and QQM will not be operated but prior to impulse reception and during impulse make periods relay P will be operated and during impulse break periods relay PP will be operated. These relays are very quick in releasing and on the change over of contact s1 they release before a holding circuit is closed by the change over of contact a1. At each impulse break, magnet SDM is energized in a circuit from earth over contacts c1, 25 b1, cb1, a2, magnet SDM to battery and winding (II) of relay C is energized by the closure of contact a3. When magnet SDM has stepped its stepping switch from normal, contact son opens 30 and relay C remains operated depending on pulses of current in its winding (II). It will release at the end of the impulse train due to the continued energization of relay A.

If, during impulsive, fleeting breaks take place 40 during a make period of an impulse, contact s1 will respond to the signal but the condition of relay A will not be changed. Consequently on contact s1 falling back, relay PP operates and prepares a holding circuit for itself at contact pp1 and when contact s1 re-makes relay PP is held and relays QB and QQB operate in this holding circuit over contact bdm of magnet BDM, contacts pp1 and a1. Contact qb1 closes the circuit of magnet BDM which operates and opens 45 the circuit of relays PP, QB and QQB at contact bdm. These relays release and open the circuit of magnet BDM which releases and steps its switch. Magnet BDM will be operated in this manner every time a fleeting break signal occurs 50 during the make portion of a standard impulse. It will now be seen without further detailed description that a fleeting make occurring during the break portion of an impulse will bring about a like operation of relays P, QM and QQM and a corresponding operation of magnet MDM. It 55 will be noticed that relays QQB and QQM are not operated until contact s1 has reverted to the position it should occupy due to standard impulsive consequently no circuit is closed for relay CA. If the number of fleeting signals is less than the number of standard impulses no further fleeting 60 impulse action will occur and no circuit will be closed for magnets BDM and MDM after the receipt of the last signal. If however there are 65 fewer standard impulses than fleeting signals and that one fleeting signal is transmitted on each portion of a standard impulse then means must be provided to prevent undesired operation of magnet SDM by the standard impulses which 70 must be transmitted in order to provide a carrier 75

for the fleeting signals. The prevention of operation of magnet SDM in such circumstances is brought about by the transmission of a special signal. This signal consists of two fleeting signals transmitted during the appropriate period of the last standard impulse to be utilized the signal being makes or breaks depending on whether one of the corresponding magnets has already ceased operation or not. If fleeting signals for the operation of magnet BDM have already ceased but fleeting makes are to be transmitted for the further operation of magnet MDM then, during the last standard impulse break two fleeting makes are transmitted in succession the second being transmitted within the operating period of the corresponding magnet. The first of these transient makes brings about the operation of relays P, QM and QQM and the second arriving before the magnet MDM has fully energized and opened contact bdm, earth is connected over contact s1, 20 rectifier R1, contacts b3, c3, qqm1, relay CA to battery. Relay CA operates and locks up over contacts ca1, rectifier R3, contacts a2, cb1, b1 and c1. When the standard impulse break is completed relay A re-operates and at contact a2 removes a short circuit from relay CB which thereupon operates in series with relay CA and remains operated for the remainder of the impulse train. Further release of relay A is thereby rendered 25 ineffective as regards magnet SDM as the magnet circuit is open at contact cb1.

If, on the other hand, signals for the operation of magnet MDM have already ceased but fleeting breaks are to continue beyond the number of standard impulses required, then during the period when relay A is operated after the last operation of magnet SDM two fleeting breaks are transmitted in succession the second being transmitted within the operating period of magnet BDM and thus relay CA is operated by the second signal in a circuit from earth over contacts s1, b2, c2 and qb1. Relay A being already energized, relay CB operates in series with relay CA on the removal of the short circuit across it 40 by the return of contact s1 to its front position and opens the circuit of magnet SDM at contact cb1. Thus further release of relay A will be without effect on magnet SDM but relay C will be maintained.

If both kinds of fleeting signals are to continue 45 beyond the number of standard impulses then the double signal will be transmitted during the break period of the last standard impulse break.

Another method which may be employed to 50 prevent operation of magnet SDM by impulses transmitted for the purpose of carrying the fleeting signals and to hold relay C until the last impulse has been received is to transmit a long train of impulses, the first 10 of which are merely 55 for the purpose of carrying the fleeting signals, assuming 10 to be the maximum number required, the remainder of the train containing as many impulses as may be necessary to operate magnet SDM to step the switch to the required 60 contacts. Contact a2 may normally be effective to cause the switch operated by magnet SDM to take 10 steps and in addition further steps depending on the digit transmitted, by this means 65 no special signal signifying the end of the fleeting impulse trains will be necessary.

A method of transmitting the fleeting signals 70 will now be described with reference to Figs. 5 and 6. Fig. 5 shows so much as is necessary of a register sender circuit in an automatic tele- 75

phone system for the understanding of the invention, the general operation of such a circuit being well known to those skilled in the art of automatic telephony. In this figure it is proposed to transmit the hundreds, tens and units digits simultaneously, the hundreds digit being transmitted as fleeting breaks during the make period of standard impulses, the tens digit being transmitted as fleeting makes during the break period of standard impulses and the units digit being transmitted as standard impulses. Of the apparatus shown SDM is the reverse drive sending switch magnet, wipers of the sending switch concerned with marking to determine the end of an impulse train being designated S₁, S₂, S₃ and S₄. Wipers H, T, and U₁, U₂, are wipers of the hundreds, tens and units digits registers which are set in accordance with the digits to be transmitted and mark appropriate contacts in the banks of the sending switch. Corresponding contacts in the banks of wipers U₁ and U₂ are connected to contacts in the banks of wipers S₃ and S₄ so that for a given position of wipers U₁ and U₂ the contacts marked in the bank of wiper S₃ is one later in the direction of rotation of the switch than that marked in the bank of wiper S₄. Relays TA and TB and TC are concerned with the termination of impulse transmission of the three digits respectively and when operated lock up over their left hand windings, and CO is the relay operated at the end of impulse transmission to bring about the release of the register controller. Relay IG is the guard relay to guard against a split first impulse being transmitted. Contacts CC₁—CC₅ are cam operated contacts which are operated in a cycle for the transmission of impulses and fleeting signals and for advancing the sending switch step by step. The times of circuit closure due to their operation in a cycle are shown diagrammatically in Fig. 6 to which a brief reference will now be made. In this figure time is measured horizontally and the period during which effective circuit closure by a cam contact occurs is indicated by a horizontal line against the contact designated at the left of the figure. The diagram has been divided by vertical lines to show the make and break periods of standard impulses. It will be seen from the figure that the make portion of an impulse is provided for by the closure of contacts CC₃ and during this time the lower contacts CC₄ and upper contacts CC₅ are closed all these contacts being open during the break portion of an impulse during which time magnet SDM is energized. It will also be seen that during the break portion of an impulse contact CC₂ which is shown as a make-before-break contact, is operated to give a fleeting make and the circuit over it remains open thereafter when the contact has changed from its back to its front position. The make through period of the contact is too short to have any operative effect on an ordinary impulse receiving relay but will operate a high speed relay connected to wires 11 and 12. Its return may take place during the period when contact CC₃ is closed so that it is ineffective or it can wait till the time when the next fleeting make is required when it can by its restoration provide the required fleeting impulse. Similarly contact CC₁ effects a fleeting break by opening for a very short period during the impulse make period.

When impulse transmission over the wires 11, 12 is to commence, contact x is closed by some

suitable means and a loop thereby completed over wire 11 contacts ig₂ and x and wire 12 and the distant impulse receiving relay is energized. A relay having contacts ss is also energized and the next time a short circuit across relay IG is removed by the opening of the upper contacts CC₄, the relay operates in a circuit over contact ss₁ to earth. Contact ig₁ changing over prevents a re-imposition of the short-circuit, and on the next closure of the upper contacts CC₄ magnet SDM 10 is operated. It is subsequently released to advance the stepping switch one step. This action occurs at each closure and opening of the upper contacts CC₄. Contacts ig₃ and ig₄ prepare circuits for relays TA and TB dependent on wipers S₁ and S₂ and contact ig₂ changing over leaves the impulsing loop dependent on contact CC₃. Contact ss₂ closes an operating circuit for relay TC over cam contacts CC₅. Neglecting for the moment operation of contacts CC₁ and CC₂ and relays TA and TB, it will be seen that each time contact CC₃ opens the loop circuit is broken and an impulse break is transmitted enduring for the standard period to allow the distant relay, such as relay A in Fig. 3 responsive to standard impulses to release and perform its function, this relay being impulsed by a repeating relay such as relay S. Reference to Fig. 6 will show however that the operation of contacts CC₁ and CC₂ will have the effect of transmitting fleeting makes and breaks during the break and make periods of the standard impulses, the loop circuit closed over contact CC₃ being opened transiently at contact CC₁ and when the loop circuit is open at contact CC₃ a fleeting closure of the circuit will occur on the make through of contact CC₂.

When the sending switch in the course of its stepping reaches a position in which earth is found on the bank of wiper S₁ over contacts ss₁, upper contacts CC₄, ig₁, ig₃ and wiper H, relay TA operates over its right hand winding and locks up over its left hand winding. Contact ta₁ short-circuits contacts CC₁ and tc₁ so that no more transient break signals are transmitted. Similarly relay TB is operated when wiper S₂ encounters a contact earthed over contacts ss₁, CC₄, ig₄ and wiper T and opening contact tb₁ prevents any further fleeting closures of the loop circuit by contact CC₂.

When wiper S₄ is stepped onto the contact marked over wiper U₂ and assuming for the moment that relays TA and TB have been operated, relay TC operates from earth over contacts ss₂, CC₅ lower, ta₃ and tb₂ and the marking circuit and at contact tc₃ completes a circuit over contacts ta₄ and tb₃ for winding (I) of relay CO. Contacts tc₁ and tc₂ are ineffective as regards the impulsing loop in the assumed circumstances.

If there are fewer impulses in the units digit than there are in the tens or hundreds digits, then relay TC operates from earth over contact ss₂, CC₅, ta₂ or tb₂ depending on whether TB or TA has been operated. This takes place as follows. If relay TA has already operated but relay TB has not and there are more fleeting makes to be sent, two fleeting makes are transmitted in succession. This takes place as follows. When wiper S₄ is stepped on to the contact marked over wiper U₂ the upper contacts CC₅ are closed and when the next standard break commences these contacts are changed over and a circuit is completed over contacts ss₂, CC₅ lower, tb₂, wipers U₂ and S₄ for relay TC. Before relay TC has time to operate fully contacts CC₂ change

over and transmit a fleeting make and this is followed very shortly by the change over of contacts *tc2* which transmit a further fleeting make. The result of this is to render the stepping switch 5 responsive to the standard impulses at the receiving end of the loop ineffective as will by this time have been understood from the description given of the operation of the circuits shown in Fig. 3. Further fleeting makes are sent by the 10 operation of contacts *CC2* during the break period of non-effective standard impulses. Similarly, if relay *TB* has been operated but relay *TA* has not and further fleeting breaks are to be transmitted two fleeting break impulses are transmitted 15 in succession. This takes place as follows: When the last standard impulse break to which response is required has been transmitted and the succeeding make period commences wiper *S3* is stepped to the contact marked over wiper *U1* and since the upper contact *CC5* is now closed relay *TC* operates in a circuit including this contact and contact *ta2*. Before relay *TC* has fully 20 operated contact *CC1* has transmitted a fleeting break in the loop and this is followed by a further fleeting break due to the change over of 25 contact *tc1* with the result that the magnet responsive to standard impulses is rendered unresponsive to further standard impulses. Further fleeting breaks are transmitted until wiper *S1* 30 encounters the contact marked over wiper *H* whereupon relay *TA* operates. Contacts *ta4*, *tb3*, *tc3* being now closed relay *CO* operates.

On the operation of relay *CO* a homing circuit is closed for the sending switch from earth over 35 contact *co1*, winding (II) of relay *CO*, off-normal contacts *on* of the switch, magnet contacts *sdm* and the switch magnet *SDM* to battery. The magnet by self-interruption drives the switch rapidly to its home position whereupon its circuit 40 is opened at contacts *on*. Relay *SS* has meanwhile been released so that relay *IG* becomes de-energized and releases. Contact *co2* maintains the loop closed until the homing has been completed and the register controller is released. 45 Relay *CO* may be held operated until all the switches in the register controller have reached their home position by the closure of a circuit for its second winding over wire *r*.

We claim:—

50 1. In a control system, an impulsing circuit, means for transmitting current impulses over said impulsing circuit by opening and closing said circuit, means for transmitting signals over said impulsing circuit by fleeting interruptions of the impulsing circuit during the impulsing period in which the impulsing circuit is closed, and means for transmitting other signals over said impulsing circuit by fleeting closures of the impulsing circuit while said impulsing circuit is open 55 during impulse transmission.

2. In a control system, an impulsing circuit, means for simultaneously transmitting more than one impulse train over said impulsing circuit, one impulse train comprising make and break impulses of the ordinary duration of said impulsing circuit, the other impulse train comprising fleeting closures of said impulsing circuit during the break period of said one impulsing train, and receiving means for differentiating between the 60 ordinary and fleeting impulse trains and operated in accordance therewith.

3. In a control system, an impulsing circuit; means for transmitting ordinary impulses over said impulsing circuit by opening and closing said 65 circuit; means for transmitting signals over said

impulsing circuit prior to, subsequent to, or during impulse transmission, each signal comprising a fleeting circuit interruption of said impulsing circuit during the period said impulsing circuit is closed; apparatus at a receiving point operative 5 in response to the receipt of said impulses and signals, and means for preventing the operation of said apparatus to record a fleeting signal in case the circuit interruption persists for a period indicative of an impulse. 10

4. In a control system, an impulsing circuit, means for transmitting ordinary impulses over said impulsing circuit by opening and closing said circuit, means for transmitting signals over said impulsing circuit, each signal comprising a fleeting circuit interruption of said impulsing circuit during the period said impulsing circuit is closed, a high speed relay at a receiving point operated in response to each signal and each impulse for repeating said impulses and signals, an impulse 15 relay controlled by said high speed relay and operated only in response to said repeated impulses, and a second high speed relay controlled by said first high speed relay dependent upon the operated condition of said impulse relay. 20

5. In a control system as claimed in claim 3 wherein the signal transmitting means includes a contact spring set in the impulsing circuit having its front contact electrically connected to its back contact and a moving part which produces 30 a fleeting circuit interruption by the change over from its back contact to its front contact when operated.

6. In a control system as claimed in claim 2 wherein said receiving means includes a relay responsive to both said ordinary impulses and said fleeting closures, a second relay controlled by said first relay and responsive only to said ordinary impulses, a third relay controlled by both said first and second relays and responsive only 35 to said other impulse train, a plurality of pieces of apparatus operated in accordance with the simultaneously transmitted impulse trains, and contacts on said second and third relays for operating said apparatus. 40

7. In a control system, an impulsing circuit, means for simultaneously transmitting more than one impulse train over said impulsing circuit, one impulse train comprising make and break impulses of the ordinary duration of said impulsing 50 circuit, the other impulse train comprising fleeting interruptions of said impulsing circuit superimposed on the make impulses of the first impulse train, a first apparatus, a second apparatus, means responsive to said one impulse train for operating said first apparatus in accordance with the impulses in said one impulse train, means responsive to said other impulse train for operating said second apparatus in accordance with fleeting interruptions in said other impulse train, 55 and means for preventing the operation of said first apparatus in response to ordinary impulses when such impulses are transmitted only for the purpose of providing means for transmitting the fleeting interruptions in said other impulse train. 60

8. In a control system as claimed in claim 7 wherein said preventing means includes a relay operated in response to receipt of two successive fleeting signals of the same nature in case the second of said signals is received before the first 70 has been fully responded to.

9. In a control system, an impulsing circuit, means for simultaneously transmitting more than one impulse train over said impulsing circuit; one impulse train comprising a fixed number of im- 75

5 pulses followed by a variable number of impulses, such impulses comprising make and break circuit closures of ordinary duration of the impulsing circuit; the other impulse train comprising 10 fleeting closures of said impulsing circuit superimposed on the break impulses of said fixed number of impulses, a first and a second apparatus, means responsive to said other impulse train for operating said second apparatus in accordance 15 with the fleeting closures in said fixed number of impulses, and means responsive only to said variable number of ordinary transmitted impulses for operating said first apparatus in accordance with the number of ordinary impulses in said 20 variable number.

10. In a telephone system, an impulsing circuit, a sending switch for transmitting trains of impulses, bank contacts in the bank of said switch corresponding in number to the number 20 of impulses in the longest single impulse train required to be sent, a register for marking certain of said bank contacts in accordance with a plurality of recorded digits, means including said switch and said marked bank contacts responsive 25 to a single rotation of said switch for simultaneously transmitting a plurality of impulse trains over said impulsing circuit in accordance with said recorded digits, one of said impulse trains comprising make and break impulses of the ordinary duration of said impulsing circuit, and another of said impulse trains comprising fleeting interruptions of said impulsing circuit superimposed on the make impulses of said one 30 impulse train.

35. 11. In a telephone system, an impulsing circuit, a sending switch for transmitting trains of impulses, bank contacts in the bank of said switch corresponding in number to the number of impulses in the longest single impulse train required 40 to be sent, a register for marking certain of said bank contacts in accordance with a plurality of recorded digits, means including said switch and said marked bank contacts responsive to a single rotation of said switch for simultaneously transmitting a plurality of impulse trains over said 45 impulsing circuit in accordance with said recorded digits, one of said impulse trains comprising make and break impulses of the ordinary duration of said impulsing circuit, another of said 50 impulse trains comprising fleeting interruptions of said impulsing circuit superimposed on the make impulses of said one impulse train, cyclically operated contacts for transmitting said fleeting interruptions during the make periods of the 55 impulsing circuit, wipers on said switch operative to engage said bank contacts, relays connected to said wipers and operated responsive to the corresponding wipers engaging its marked bank contact, and means controlled by said relays 60 when operated for disabling said cyclically operated contacts to transmit further fleeting interruptions of said impulsing circuit.

12. In a telephone system, an impulsing circuit, a sending switch for transmitting trains of 65 impulses, bank contacts in the bank of said switch corresponding in number to the number of impulses in the longest single impulse train required to be sent, a register for marking certain of said bank contacts in accordance with a plurality of recorded digits, means including said switch and said marked bank contacts responsive to a single rotation of said switch for simultaneously transmitting a plurality of impulse trains over said 70 impulsing circuit in accordance with said recorded digits, one of said impulse trains

comprising make and break impulses of the ordinary duration of said impulsing circuit, another of said impulse trains comprising fleeting closures of said impulsing circuit superimposed on the break impulses of said one impulse train, cyclically operated contacts for transmitting said fleeting closures during the break periods of said impulsing circuit, wipers on said switch operative to engage said bank contacts, relays connected to said wipers and operated responsive to the corresponding wipers engaging its marked bank contact, means controlled by said relays when operated for disabling said cyclically operated contacts to transmit further fleeting closures of said impulsing circuit, receiving apparatus operated in accordance with said transmitted impulse trains, means controlled by a particular one of said relays if operated before the other of said relays, for transmitting an additional fleeting signal immediately before or after the signal of the same nature transmitted by the cyclically operated contacts, and means for disabling said receiving apparatus in response to the receipt of said additional transmitted fleeting signal.

13. In a control system, an impulsing circuit, means for transmitting ordinary impulses over said impulsing circuit by opening and closing said circuit, means for transmitting signals over said impulsing circuit prior to, subsequent to, or during impulse transmission; each signal comprising a fleeting circuit closure of said impulsing circuit during the period said impulsing circuit is open, apparatus at a receiving point operative in response to the receipt of said impulses and signals, and means for preventing the operation of said apparatus to record a fleeting signal in case the circuit closure persists for a period indicative of an impulse.

14. In a control system as claimed in claim 13 wherein the signal transmitting means includes a make-before-break spring set in the impulsing circuit for producing a fleeting circuit closure only during the make-through operating period of said spring set.

15. In a control system, an impulsing circuit, means for transmitting ordinary impulses over said impulsing circuit by opening and closing said circuit, means for transmitting signals over said impulsing circuit prior to impulse transmission, each signal comprising a fleeting circuit interruption of said impulsing circuit, apparatus at a receiving point operative in response to the receipt of said impulses and signals, means for preventing the operation of said apparatus to record a fleeting signal in case the circuit interruption persists for a period indicative of an impulse; said signal transmitting means including a condenser, a relay and means for charging said condenser to momentarily operate said relay to transmit a fleeting signal.

16. In a control system, an impulsing circuit, means for transmitting ordinary impulses over said impulsing circuit by opening and closing said circuit, means for transmitting signals over said impulsing circuit prior to impulse transmission, each signal comprising a fleeting circuit interruption of said impulsing circuit, apparatus at a receiving point operative in response to the receipt of said impulses and signals, means for preventing the operation of said apparatus to record a fleeting signal in case the circuit interruption persists for a period indicative of an impulse; said signal transmitting means including a condenser, a relay connected in series with said condenser, a source of current, and off-normal springs on a

number dial to charge said condenser from said source to momentarily operate said relay to transmit a fleeting signal.

17. In a control system, an impulsing circuit, 5 means for simultaneously transmitting more than one impulse train over said impulsing circuit; one impulse train comprising make and break impulses of ordinary duration of the impulsing circuit, the second impulse train comprising fleeting 10 circuit interruptions of said impulsing circuit

superimposed on the make impulses of the first impulse train, and the third impulse train comprising fleeting circuit closures of said impulsing circuit superimposed on the break impulses of the first impulse train; and a first, a second and a third apparatus operated in response to said three impulse trains. 5
